CLAIM

The ornamental design for a dog cage, as shown and described.

DESCRIPTION

FIG. 1 is a front perspective view of embodiment 1, showing my new design;

FIG. 2 is a rear perspective view thereof of embodiment 1;

FIG. 3 is a front view thereof of embodiment 1;

FIG. 4 is a rear view thereof of embodiment 1;

FIG. 5 is a left side view thereof of embodiment 1;

FIG. 6 is a right side view thereof of embodiment 1;

FIG. 7 is a top view thereof of embodiment 1;

FIG. 8 is a bottom view thereof of embodiment 1;

FIG. 9 is a front perspective view of embodiment 2;

FIG. 10 is a rear perspective view thereof of embodiment 2;

FIG. 11 is a front view thereof of embodiment 2;

FIG. 12 is a rear view thereof of embodiment 2;

FIG. 13 is a left side view thereof of embodiment 2;

FIG. 14 is a right side view thereof of embodiment 2;

FIG. 15 is a top view thereof of embodiment 2;

FIG. 16 is a bottom view thereof of embodiment 2;

FIG. 17 is an enlarged detail view of area 17 in FIG. 1; and,

FIG. 18 is an enlarged detail view of area 18 in FIG. 1.

The broken lines in the drawings illustrate the portions of the dog cage, which form no part of the claimed design.

The dash-dot-dash broken lines encircling the enlarged views are for annotative purposes only and form no part of the claim thereof.

1 Claim, 18 Drawing Sheets
